P. S. FITZGERALD,
RAPID LOADER FOR WAGONS,
APPLICATION FILED Aug. 22, 1914.

Patented May 9, 1916.

2 SHEETS-SHEET 2.

UNITED STATES PATENT OFFICE.

PHILIP S. FITZGERALD, OF ROCHESTER, NEW YORK, ASSIGNOR TO THE BONNEY SUPPLY CO., INC., OF ROCHESTER, NEW YORK, A CORPORATION OF NEW YORK.

RAPID LOADER FOR WAGONS.

1,182,081

Specification of Letters Patent. Patented May 9, 1916.

Application filed August 22, 1914. Serial No. 858,136.

To all whom it may concern:

Be it known that I, PHILIP S. FITZGERALD, a citizen of the United States, residing at Rochester, in the county of Monroe and State 5 of New York, have invented certain new and useful Improvements in Rapid Loaders for Wagons, of which the following is a specification.

The object of this invention is to provide 10 a loading device that can be filled and quickly dumped to load a wagon or other vehicle.

Another object of this invention is to make it portable so that it can be conveniently applied to the sides of freight cars.

15 These and other objects of this invention, will be fully illustrated in the drawings, described in the specification and pointed out in the claims at the end thereof.

In the drawings, Figure 1 is a side elevation of my rapid loader attached to the side 20 of a freight car. Fig. 2 is a front elevation of my improved loader viewed from the left in Fig. 1. Fig. 3 is a cross section on the line 3^x—3^x of Fig. 1. Fig. 4 is a rear 25 elevation of my improved loader viewed from the right in Fig. 1. Fig. 5 is a vertical section of the pan or tipple the section being taken on the line 5^x—5^x of Fig. 4. Fig. 6 is a vertical section on the line 6^x—6^x of 30 Fig. 5.

In the drawings, like reference numerals indicate like parts.

My improved loader is made of a supporting device and a tipple or pan pivotally 35 mounted in the supporting device. The supporting device consists of brackets 1 and 2 shown in Fig. 2 which brackets are substantially alike except that the angle members of which they are made, are arranged 40 with their flanges to the right in one case and to the left in the other, the flanges being preferably placed on the inside of the finished structure, and extending perpendicular to the body of the car on which they 45 are placed, the webs of the angles extending parallel to the body of the car.

As shown in Fig. 1, the bracket 1 is triangular in shape, the angle member 3 forming the hypotenuse. The upright member 50 4 is provided and between the member 3 and the member 4 is placed the foot 5 of the bracket, the members 3 and 4 being welded to the opposite sides of the foot 5, or fastened together by rivets or any other suitable 55 manner. The end of the foot 5 is turned

up at right angles as indicated at the bottom of Fig. 2 to afford a suitable bearing with which it may rest against the side of the car. The top member 6 is likewise fastened to the members 3 and 4 so as to join them together and hold them in the relation as shown in Fig. 1.

The top member 6 extends to the right as is shown in Fig. 1 so as to overhang the top edge of the car. At the right hand end, the 65 top member 6 has fastened thereto, a short piece of angle so as to form a channel 7 thereon, through the parallel sides of which channel, perforations are made to receive the pin 8 by which pin, the top of the bracket 70 hooks over the top of the side of the car for the purpose of holding the bracket in place. A series of perforations are provided in this channel so that the pin may be set in any desired position and fit over the side of a car 75 of any thickness, the adjustment being preferred that will hold the upright member 4 parallel to the side of the car.

The left hand end of the angle 6 has its web cut away where it overlaps with the 80 member 3 and both of these members are recessed at 9 to form a bearing for the ends of the shaft 10 of the tipple.

The tipple as shown in Fig. 5 consists of a pan made preferably of sheet metal, which 85 pan is preferably open on two sides and closed on four sides. The two sides 18 and 19 are alike except that they are made right and left and have preferably the shape of an oblique parallelogram. Located slightly 90 above the center of gravity of the tipple as shown in Fig. 5 and passing through the sides 18 and 19, is the shaft 10 by which the tipple is supported, the shaft 10 being located so that the weight of the material as 95 the tipple is filled by shoveling from the car, will normally hold it in the horizontal position shown in full lines in Fig. 1. The shaft 10 extends lengthwise through the tipple, or parallel to the car body, from one 100 bracket to the other as is shown in Fig. 4 and has gudgeons at each end which engage with the bearings in the brackets. The sides 18 and 19 of the tipple where the shaft 105 extends through is reinforced by plates or angles 11 and the edges 12 and 13 of the tipple are reinforced with angles as is the front and back at 14 and 15. Reinforcing angles are also provided at 16 and 17 on the bottom. The bottom 20 and end 21 are 110

formed of a single plate of metal, the edges of which are turned down to form flanges as shown in section in Fig. 6. The shaft 10 is perforated just outside of the sides 18 and 19 to receive the pins 22 and 23 by which the sides are held against expanding. Inside of each of the sides 18 and 19 are provided the reinforcing plates 24 and 25 to increase the bearing surface between the tipple and the shaft.

16 Mounted in the channels 7 are locking pins 26 which pass vertically through the channel, and have their upper ends turned inwardly over the channel and tipple and their lower ends turned outwardly under the channel to form a handle for the operation of the pin. When the tipple is in the full line position shown in Fig. 1, the pins will be turned to locking position, in which position they will engage the tipple and hold it against turning. When it is desired to dump the tipple the pins will be turned a quarter turn releasing the tipple for turning it.

25 In practice, the brackets 1 and 2 are placed on the side of the freight car and are fastened in place by the pins 8. These brackets are then connected by the braces 26 and 27 which connect them together and hold them 30 suitably spaced apart. The tipple is then put in position with the ends of its shaft resting in the bearings 9 at the upper ends of the brackets with the inner end of the tipple resting upon the top of the side of the 35 car and the bottom of the tipple substantially horizontal. In this position, the tipple is ready to receive a load and is filled by shoveling from within the car. One or more of these tipples can be used on the car as may 40 be desired, it being preferably to use two as it is intended that the contents of two of these tipples will be sufficient to fill the body of an ordinary dump wagon. These tipples are then filled and when they are filled are 45 ready to be dumped. The wagon is first placed under one of these tipples which tipple is dumped by simply raising the right hand end as shown in Fig. 1. After the 50 tipple is dumped, it will return to normal full line position and the wagon can proceed to the second tipple which will be dumped in the same manner.

I claim:

1. In a loading apparatus, the combination of a support, a pair of brackets, mounted on said support, and a tipple pivotally mounted on said brackets slightly above its center of gravity and having one edge normally resting lightly on said support, said 55 tipple being easily turned on its brackets to discharge its contents on the side opposite the support.

2. A tipple for a loading apparatus comprising a body having two parallel sides, 60 each of which is substantially of the shape

of a rhomb with the bottom connected to two adjacent edges of each of said sides, and a shaft extending across said tipple and passing through the sides at a point substantially midway between the top and bottom edges 70 and between the front and back edges.

3. A tipple for a loading apparatus, having two equal sides, each side having the shape of an oblique parallelogram, a bottom and an end connected to said sides, said bottom being bent across substantially its center to form oppositely inclined portions, one of which lies substantially horizontal when the tipple is in its loading position.

4. A tipple for a loading apparatus having two equal sides, each having the shape of an oblique parallelogram, a bottom and an end connected to said sides, said bottom being bent across substantially its center to form oppositely inclined portions one of 85 which lies substantially horizontal when the tipple is in its loading position, and supports extending from said sides above the center of gravity thereof.

5. In a loading apparatus, a support composed of a pair of brackets each having substantially the shape of an obtuse triangle with the base of the triangle placed upright, the sides of the triangle extending upwardly and outwardly beyond the upper end of the 95 base, and provided with projections, the other end of the side engaging with the hypotenuse and having a bearing thereon, in combination with a tipple pivotally hung substantially midway of its longitudinal and 100 transverse axes between the upward and outward extentions of said triangles.

6. In a loading apparatus, a support composed of a pair of brackets, each having substantially the shape of an obtuse triangle 105 with the base of the triangle placed upright, a foot at the lower end of said base extending upwardly therefrom, the side of the triangle extending upwardly and outwardly beyond the upper end of the base and having the inner end provided with a projection, the other end of the side engaging with the hypotenuse and having a bearing thereon, and braces connecting said brackets and holding them suitably spaced apart, in combination with a tipple pivotally hung substantially midway of its longitudinal and 115 transverse axes between the upward and outward extentions of said triangle.

7. In a loading apparatus, the combination of a support comprising a pair of brackets with braces connected thereto by which said brackets are suitably spaced apart, bearings in said brackets, a tipple having gudgeons located approximately at the 120 longitudinal and transverse center of the sides thereof adapted to engage with said bearings and to be supported thereby.

8. In a loading apparatus, the combination of a support comprising a pair of 130

- brackets with braces connected thereto by which said brackets are suitably spaced apart, bearings in said brackets, a tipple having gudgeons located approximately at 5 the longitudinal and transverse center of its sides adapted to engage with said bearings and to be supported thereby, said tipple being open on two adjacent sides and permanently closed on its four other sides.
- 10 9. In a loading apparatus, the combination of a support comprising a pair of brackets with braces connected thereto by which said brackets are suitably spaced apart, bearings in said brackets, a tipple 15 having gudgeons located approximately at the longitudinal and transverse center of its sides adapted to engage with said bearings and to be supported thereby, the sides supporting the said gudgeons having the shape 20 of an oblique parallelogram.
10. In a loading apparatus, a support composed of a pair of brackets each having substantially the shape of an obtuse triangle with the base of the triangle placed upright, the side of the triangle extending upwardly 25 and outwardly beyond the upper edge of the base and having an inner end provided with a projection, the other end of the side engaging with the hypotenuse and having a bearing thereon, in combination with a tipple pivotally hung between its ends and at a substantial distance from its top and bottom edges, between the upward and outward extension of said triangles. 30
- In testimony whereof I affix my signature 35 in presence of two witnesses.

PHILIP S. FITZGERALD.
